BOAT WISHBONE

Richard G. Reineman, Balboa, Calif., assignor to Bruns-Wick Corporation, a corporation of Delaware

Filed Oct. 9, 1967, Ser. No. 8,921

Term of patent 14 years

U.S. Cl. D71—1
Int. Cl. D12—06

FIG. 1 is a rear perspective view of a boat wishbone embodying my new design with the boat shown in broken lines for illustrative purposes only;

FIG. 2 is a front perspective view of the wishbone; and

FIG. 3 is a side elevational view thereof.

The dominant features of the design reside in the portion of the article shown in full lines.

I claim:

The ornamental design for a boat wishbone, as shown and described.
